CLAIM

The ornamental design for an applicator head, as shown and described.

DESCRIPTION

FIG. 1 is a front right perspective view of an applicator head showing my new design.

FIG. 2 is a front elevation view of FIG. 1.

FIG. 3 is a rear elevation view of FIG. 1.

FIG. 4 is a left side elevation view of FIG. 1.

FIG. 5 is a right side elevation view of FIG. 1.

FIG. 6 is a top plan view of FIG. 1; and,

FIG. 7 is a bottom plan view of FIG. 1.

The broken lines depict environmental subject matter and form no part of the claimed design.

1 Claim, 7 Drawing Sheets
